DESIGN FOR A SHOE

Jack C. Fishman, New York, N. Y.

Application February 23, 1940, Serial No. 90,442

Term of patent 3½ years

To all whom it may concern:

Be it known that I, Jack C. Fishman, a citizen of the United States of America, residing in city of New York, county of New York, and State of New York, have invented a new, original, and ornamental Design for a Shoe, of which the following is a specification, reference being had to the accompanying drawing, forming part thereof.

Fig. 1 is a perspective view of a shoe showing my new design.

Fig. 2 is a side elevational view thereof.

I claim:

The ornamental design for a shoe, substantially as shown.

JACK C. FISHMAN.
